UNITED STATES PATENT OFFICE.

CHARLES FELL, OF ELYRIA, OHIO, ASSIGNOR TO NATIONAL TUBE COMPANY, OF PITTSBURGH, PENNSYLVANIA, A CORPORATION OF NEW JERSEY.

GALVANIZING-FURNACE.

1,156,353.

Specification of Letters Patent. Patented Oct. 12, 1915.

Application filed November 12, 1914. Serial No. 871,741.

To all whom it may concern:

Be it known that I, CHARLES FELL, a citizen of the United States, and resident of Elyria, in the county of Lorain and State of Ohio, have invented certain new and useful Improvements in Galvanizing-Furnaces, of which the following is a specification.

My invention relates to the construction of galvanizing furnaces, and while not restricted to such use, more particularly relates to the construction of the galvanizing pot of furnaces used in galvanizing metal pipes. Such galvanizing pots are cast or are built up of wrought metal plates. It has been found that the life of such pots, which are cast or are built up of wrought metal plates, is very much shortened by the action of the intense heat at the junction of the sides and ends with the bottom of the pot, both in the cast form and the built up wrought metal construction.

One object of my invention is to provide a furnace galvanizing pot having novel means whereby cracking or breaking of the pots adjacent to the corners formed at the intersections of the side walls with the bottom and end walls, is overcome and prevented.

Still further objects of my invention will become apparent hereinafter as the invention becomes more fully described and specifically pointed out in the appended claims.

Referring now to the drawings forming a part of this specification, Figure 1 is a sectional plan showing a galvanizing furnace having a galvanizing pot constructed and arranged in accordance with my invention, the section being taken on the irregular line I—I of Fig. 3. Fig. 2 is a longitudinal side elevation partly in section, the section being taken on the irregular line II—II of Fig. 1. Fig. 3 is a sectional end elevation on the line III—III of Fig. 1. Fig. 4 is a sectional elevation taken on the line IV—IV of Fig. 1. Fig. 5 is a detail in sectional elevation showing the location of the cooling means relative to the corner connecting the side and bottom of the galvanizing pot. Fig. 6 is a similar sectional elevation showing the location of the cooling means at the corner formed by the end and bottom of the galvanizing pot.

In the accompanying drawings, the numeral 2 designates a galvanizing pot having a bottom 3, ends 4, 4 and sides 5, 5 formed of rolled metal plates. The plate forming

the bottom 3 of the pot is bent at its ends to form integral ends 4, 4 for the pot, and the side edges of the plate forming the bottom 3 and ends 4, 4 are provided with flanges 6 by which the side plates 5, 5 are riveted to the bottom and end members of the galvanizing pot (see Figs. 1, 5 and 6). A rolled metal angle 7 is riveted by one leg to the upper marginal edges of the sides and ends of the pot, as will be seen by reference to Figs. 5 and 6.

The galvanizing pot or kettle 2 is surrounded by the refractory walls of the furnace with the open top of the pot at about the level of the brickwork of the furnace. Extending horizontally and lengthwise parallel with the length of the furnace are draft flues 8, 9, and 10 which are connected at their ends by cross flues 11 and which deliver the products of combustion to the flue 9^a which extends from the furnace to a stack, (not shown).

The tops of the flues 8 and 10 are connected to the lower ends of a series of vertical flues 12 which open at their upper ends through ports 13 into the combustion chambers 14, a plurality of which are provided at each side of the galvanizing pot. The draft flues 8, 9, and 10 also are connected to the lower ends of vertical flues 15 which open at their upper ends through ports 16 into the combustion chambers 17 at the ends of the pot 2.

As will be seen by reference to Figs. 2 and 3 the side plates 5 and end plates 4 of the pot 2 form one wall of the vertical flues so that the heated gases will come in direct contact with the metal plates forming the pot. The upper side of the draft flue 9 also has an opening 9^b therein to permit the heated gases or products of combustion contacting directly with the bottom plate 3 of the pot 2. (See Fig. 3.)

Extending lengthwise and parallel with the length of the furnace, below the combustion chambers 14 and above the horizontal draft flues 8 and 10 are gas flues 18 and 19, ports 20 connecting the flues 18, 19 with the combustion chambers 14 and 17 and a movable tile 21 being employed to regulate the size of the ports 20 and control the flow of gas into the combustion chambers. An air port 22 connects into each combustion chamber at the bottom thereof to admit the air necessary to support combustion in the

combustion chambers and the tiles 21 are conveniently adjusted through the air ports 22 in regulating the amount of gas passing into each combustion chamber. A transverse 5 flue 23 connects the gas flues 18 and 19 with the gas ports 24 opening through the bottom thereof into the combustion chambers 17 at the ends of the galvanizing pot.

The gas flues 18 and 19 are connected at 10 one end of the furnace by vertical flues 25 to the gas flues 26, 27 leading from a gas producer or other source of gas supply.

The refractory walls of the galvanizing furnaces are stayed in the usual known manner 15 by the use of buckstaves 28, 29 on the sides and ends of the furnaces.

Extending lengthwise from one end to the other of the galvanizing pot on each side of the riveted joint formed at the junction 20 of the plate forming the bottom 3 and ends 4 with each plate 5 forming the vertical side wall of the pot 2, is a water pipe 30, these pipes being bent at the ends of the pot to extend vertically upwardly in close proximity 25 to the joint formed by the side plates with the end of the galvanizing pot and extending upwardly through the brick work of the furnace to a point where they are connected to a suitable source of supply and to 30 an overflow outlet opening.

In constructing the furnace the pot is fabricated in the usual manner and the refractory furnace is constructed to a suitable height to place the galvanizing pot 2 in position. The bent pipes 30 are then positioned 35 in the walls of the galvanized furnace and the galvanizing pot is also positioned as shown in the furnace. The refractory lining or brick work is then completed and after 40 the buckstaves have been placed in position the furnace is ready for use. The furnace is then employed in the usual manner, being first filled with spelter which becomes molten by the action of the heated gases, which in 45 passing from the combustion chambers come into contact with the walls of the galvanizing pot.

When the furnace is started in operation 50 water or other cooling medium is caused to circulate through the cooling pipes so that

the joints in the plates of built up pots such as those shown in the drawings are kept relatively cool, and over-heating of the pot at the joints is thereby prevented so that liability of cracking or breakage is greatly reduced and the life of the pots very materially increased. 55

Instead of employing galvanizing pots built up of wrought metal plates, with pipes to conduct the cooling medium as shown, the 60 pots may be cast with conduits formed therein to carry the cooling medium, or the pipes may be cast in the body of the cast metal galvanizing pots.

The advantages of my invention will be 65 apparent to those skilled in the art. By the provision of a pipe or similar conduit to conduct a cooling medium to points adjacent to the junction of the side and end walls with the bottom of the pot, the life of the pots is 70 greatly increased and the cost of maintaining the galvanizing furnaces in operative condition is materially reduced.

Modifications in the construction and arrangement of the furnace and in the galvanizing pot may be made without departing 75 from my invention as defined in the appended claims.

I claim:

1. In a galvanizing furnace, a galvanizing 80 pot, means for heating the pot, and a conduit adjacent to the intersection of the side walls with the bottom of the pot to conduct a cooling medium therethrough and prevent over-heating the pot at the junction of the 85 sides and bottom thereof.

2. A galvanizing furnace comprising a built up galvanizing pot formed of metal plates riveted together at the intersection 90 of the side walls with the bottom and end walls, and pipes adjacent to the riveted joints in said pot arranged to convey a cooling medium therethrough and thereby prevent over-heating of the joints of said pot.

In testimony whereof, I have hereunto set 95 my hand.

CHARLES FELL.
